J. A. Reed Littell,

UNITED STATES PATENT OFFICE.

FREDRICK S. DICKINSON, OF NEW YORK, N. Y., ASSIGNOR TO PERFECTION TIRE & RUBBER COMPANY, A CORPORATION OF DELAWARE.

DESIGN FOR A TIRE-CASING.

58,181.

Specification for Design.

Patented June 21, 1921.

Application filed December 30, 1919. Serial No. 348,482. Term of patent 14 years.

To all whom it may concern:

Be it known that I, FREDRICK S. DICKINSON, a citizen of the United States, and resident of New York, in the county and State of New York, have invented a new, original, and ornamental Design for Tire-Casings, of which the following is a specification, reference being had to the accompanying drawing, forming part thereof.

Figure 1 is a plan view of a portion of the tread of a tire casing, showing my new design.

Fig. 2 is a cross-section on the line 2—2, Fig. 1.

Fig. 3 is a cross-section on the line 3—3, Fig. 1.

The features of my design comprise a ridge, as shown at 1, extending circumferentially at the center of the tread of the tire casing and having a plane surface, said center ridge being connected by cross-webs or ridges, as shown at 8, with the respective sections of a series of plane-surface ridges, as shown at 5, the respective series of which extend at each side of said center ridge. Said outer series of ridges 5 respectively extend circumferentially of the tread of the tire casing and are separated from the intermediate center ridge by grooves or depressions, as shown at 6, the respective sections

constituting said outer series of ridges being separated by intermediate grooves or depressions, as shown at 7, extending transversely and diagonally or at an angle to the longitudinal plane of said outer series of ridges and intersecting the grooves or depressions 6 at the sides of the center ridge 1. The cross-web or ridge 8 between each section of the series of outer ridges 5 and the center ridge 1 has a plane-surface and extends transversely of the groove or depression 6 at the side of the center ridge.

In the leading features of the design, embodying the associated contour as above set forth, the diagonally-extending grooves 7 of the respective side series are in the same cross-angle plane transversely of the tire, and the cross-webs 8 of the respective side series are in staggered or alternate position with relation to the transverse plane of the tire, and the relative position of the respective side series of outer ridges 5 is thus also staggered.

I claim:

The ornamental design for a tire casing, substantially as shown and described.

In testimony whereof I have signed the foregoing specifications.

FREDRICK S. DICKINSON.
